US00D638345S

(12) **United States Design Patent**
Kanczuzewski et al.

(10) **Patent No.:** **US D638,345 S**
(45) **Date of Patent:** ** *May 24, 2011

(54) **CARGO RESTRAINT DEVICE**

(75) Inventors: **Thomas E. Kanczuzewski**, South Bend, IN (US); **John W. Doster**, Granger, IN (US); **John E. Townsend**, Paw Paw, IN (US); **Donald J. Nagy**, South Bend, IN (US); **James Doster**, South Bend, IN (US)

(73) Assignee: **Logistick, Inc.**, South Bend, IN (US)

(**) Term: **14 Years**

(21) Appl. No.: **29/378,005**

(22) Filed: **Oct. 28, 2010**

(51) **LOC (9) Cl.** **12-16**

(52) **U.S. Cl.** **D12/406**

(58) **Field of Classification Search** D12/413, D12/414, 406, 412, 414.1; 293/37.1, 3, 100; 224/309-310, 315-316, 323-329, 400; D6/552, D6/317-319, 513-514; D3/304-306; 280/760-762, 280/848, 727, 769; 296/99.1, 37.1, 100.01, 296/100.02, 157; 206/213, 8, 9, 279, 290, 206/713, 335, 315.1-315.4; D32/35, 58

(74) *Attorney, Agent, or Firm* — Barnes & Thornburg LLP

(57) **CLAIM**

The ornamental design for a cargo restraint device, as shown and described.

DESCRIPTION

FIG. 1 is a top perspective view of the cargo restraint device; FIG. 2 is a bottom perspective view of the cargo restraint device;

FIG. 3 is a rear view of the cargo restraint device;

FIG. 4 is a front view of the cargo restraint device;

FIG. 5 is a top view of the cargo restraint device;

FIG. 6 is bottom view of the cargo restraint device;

FIG. 7 is a side view of the cargo restraint device; and,

FIG. 8 is an other side view of the cargo restraint device.
